PACKAGE CARRIER

Pearl M. Griffin, Hallock, Minn.

Application January 2, 1948, Serial No. 51

7 Claims. (Cl. 229—52)

2

My invention relates to an improvement in package carrier wherein it is desired to provide a package provided with a handle suitable for use in carrying the package.

A feature of the present invention lies in the fact that the handle cords for carrying the package encircle the major portion of the package, thereby effectively supporting the package. These cords bear against the outer surface of the package throughout most of the periphery thereof and take much of the strain of the weight within the package.

A feature of the present invention lies in the provision of a package having a retuckable closure in one side thereof and in arranging the handle cords so that they hold this closure in closed position as the package is carried. Thus while the package may be easily opened when it is desired to obtain access to the interior thereof, the weight of the package acts upon the handle cords to hold the package closed as it is being carried.

A feature of the present invention lies in the provision of a flexible cord handle which is designed to encircle much of the package at two spaced points and which may be easily disengaged from package encircling position when the pulling strain on the handles is lessened. As a result the carrier cord may act to reinforce the package and hold it closed while it is being carried and at the same time may be readily disengaged from the package when the same is to be opened.

These and other objects and novel features of my invention will be more clearly and fully set forth in the following specification and claims.

In the drawings forming a part of my specification:

Figure 1 is a perspective view of my package carrier showing the construction thereof.

Figure 2 is a sectional view through the package showing the manner in which the handle cords encircle the body thereof.

Figure 3 is a view similar to Figure 2 showing the closure side of the package in partially opened position.

Figure 4 is a diagrammatic view of the blank of which the package may be formed.

The package carrier A includes a top panel 10, a back panel 11, a bottom panel 12, a front closure panel 13, and a closure tuck flap 14. The top panel and the back panel are connected along the fold line 15. The back panel 11 is connected to the bottom panel 12 along the fold line 16. The bottom panel 12 is connected to

the front panel 13 along the fold line 17. The front panel 13 is connected to the tuck flap 14 along the fold line 19. All of the fold lines described are preferably parallel.

5 An end wall 20 is foldably connected to the rear panel 11 along the fold line 21. An end panel 22 is foldably connected to the rear panel 11 along the fold line 23. Locking flaps 24 and 25 are foldably connected to the top panel 10 along extensions of the fold lines 21 and 23 respectively. Similar locking flaps 26 and 27 are foldably connected to the bottom panel 12 along extensions of these fold lines 21 and 23.

The locking flaps 24 and 26 are provided with

15 suitably shaped hoop ends 28 and 29 to engage in slots 30 and 31 of the end panel 20. The locking flaps 25 are also provided with hook ends 32 and 33 which are engageable in suitable locking slots 33 and 34 of the end panel 22.

20 Thus when the end walls 20 and 22 are folded into right angular relation with the rear panel 11 and the top and bottom panels 10 and 12 are likewise folded into right angular relation to the base panel 11, a tray shaped body is formed.

25 When the various locking flaps are engaged in their respective slots, the top, bottom and end walls are held in rectangular relationship and at right angles to the rear wall 11. A pair of transversely spaced apertures 35 and 36 are provided

30 in the top panel 10 and are preferably approximately centrally located thereon. A second pair of apertures 37 and 39 are transversely aligned on the top wall 10 on the opposite side of the center of this top panel. An aperture 40 is pro-

35 vided in the panel 11 in alignment with the apertures 35 and 36 in flat condition of the blank and spaced from the fold line 15. A similar aperture 41 is aligned with the apertures 37 and 39 and is disposed on the opposite side of the fold line 15 from these apertures in the top panel.

40 A cord handle or handle of other suitable flexible material is indicated in Figures 1 to 3 of the drawings and is indicated in general by the num-

45 ber 42. This handle is of proper length to encircle the walls of the package at two spaced points between the ends thereof. A cord 42 ex-

50 tends through the aperture 37 in the top panel 10 and extends out through the spaced aperture 41 in the rear panel 11. The handle then ex-
55 tends downwardly to the bottom of the rear panel 11 forwardly beneath the bottom panel 12 and upwardly throughout the length of the front closure panel 13. The cord then extends be-
tween the tuck flap 14 and the top panel 10 until it emerges through the aperture 39.

The portion of the handle 42 projecting above the top panel 10 from the aperture 37 forms an upwardly extending handle loop 43 and then extends downwardly through the aperture 35. The cord emerges from the rear panel 11 through the aperture 40 and extends downwardly about the outer surface of the rear panel, beneath the bottom panel 12 and outwardly of the front closure panel 13. The handle cord then extends inwardly beneath the top panel 10 between the tuck flap 14 and the panel 10 to emerge through the aperture 36. The portion of the handle emerging from the aperture 36 is connected to that portion of the handle emerging from the aperture 39 to form a second handle loop 44. Obviously the handle cord is endless and must be formed by tying or otherwise fastening the ends thereof together as indicated at 46.

When the package is opened, it is usually laid down upon its rear panel 11 and the downwardly extending loops extending below the bottom panel 12 of the carton are swung over the ends thereof as indicated in dotted outline in Figures 1 and 3 of the drawings. When the handle cord is in this dotted line position the closure panel 13 may be opened so as to obtain access to the interior of the package. In closing the package it is only necessary to swing the closure panel 13 closed with the tuck flap 14 extending inwardly of the top panel 10 and swinging the handle cord so that it extends between this tuck flap and the top panel. The downwardly extending handle loops may then be swung into the position shown in full lines in Figures 1 and 2 of the drawings. The package may then be carried by the handle loops 43 and 44, the cords holding the front closure in closed position.

In accordance with the patent statutes, I have described the principles of construction and operation of my package carrier and while I have endeavored to set forth the best embodiment thereof, I desire to have it understood that obvious changes may be made within the scope of the following claims without departing from the spirit of my invention.

I claim:

1. A package carrier including a carton having rectangularly arranged panels, one of which forms a closure panel hingedly connected along a fold line to another of said panels, and a handle cord extending outwardly of the closure panel and the panel to which the closure panel is hinged, said cord extending outwardly of the panel opposite said closure panel to a point spaced from the fourth panel, said cord extending through the third mentioned panel and through the fourth panel, the other end of said cord extending between said closure panel and said fourth panel and extending through said fourth panel in spaced relation to the first named end of said cord handle.

2. A package carrier including a package having a top wall, a bottom wall, and parallel connecting side walls, one of said side walls being hingedly connected to the bottom wall, a pair of transversely spaced apertures in said top panel, and a third aperture in the side wall panel opposite said closure panel, the cord handle form-

ing a loop above said top panel and extending through said openings in said top panel, one portion of the cord extending beneath said top panel and between said top panel and said closure panel, and extending outwardly of said closure panel, the other end of said loop extending through said opening in said panel opposite said closure panel and extending downwardly outwardly of said last named panel and beneath said bottom panel to connect with the other end of said cord.

3. A package carrier for use with a package having a top panel, a rear panel, a bottom panel, and a front closure panel hingedly connected to said bottom panel, a pair of transversely spaced openings in said top panel and a third aperture in said rear panel, and a flexible handle extending through one of said spaced apertures and emerging from said third aperture, said handle extending outwardly of the rear wall, below the bottom wall, and forwardly of the front wall, and extending between the free edge of said front wall and beneath said top panel to emerge from the second of said spaced openings therein.

4. A package carrier for use in conjunction with a package having a top panel, a rear panel, a bottom panel, and a front panel hingedly secured to said bottom panel, two spaced pairs of laterally aligned apertures in said top panel, and a corresponding aperture near the top of the rear panel aligned with each pair of top panel apertures, and a flexible handle, said handle forming a first loop above said top panel and extending through one aperture of each pair, and emerging from the aligned apertures in the rear panel, said handle extending outwardly of said rear panel, beneath said bottom panel and forwardly of said front panel, and extending between the free edge of said closure panel and the bottom surface of said top panel to emerge through the other apertures of said pair, the last named emerging handle portions being connected to form a second handle loop above said top panel.

5. The structure described in claim 4 and including a tuck flap on the upper extremity of said closure panel foldable beneath said top panel.

6. The structure described in claim 4 and including end panels connected to said top panel, said rear panel and said bottom panel.

7. The structure described in claim 4 in which the handle loops are of sufficient length to permit the portions of the handle encircling the rear panel, bottom panel, and front panel to be swung off from the ends of said panels.
